CLAIM

The ornamental design for a refrigerator door panel with eye-level controls, as shown.

DESCRIPTION

FIG. 1 is a perspective view of a refrigerator door panel with eye-level controls showing our new design;

FIG. 2 is a front elevational view thereof;

FIG. 3 is a left side elevational view thereof;

FIG. 4 is a right side elevational view thereof;

FIG. 5 is a top plan view thereof;

FIG. 6 is a perspective view of a second embodiment of a refrigerator door panel with eye-level controls showing our new design;

FIG. 7 is a front elevational view thereof;

FIG. 8 is a left side elevational view thereof;

FIG. 9 is a right side elevational view thereof.
